UNITED STATES PATENT OFFICE.

JARRET C. HOLCOM, OF SULPHUR SPRINGS, TEXAS.

LEAF-TURNER.

1,364,992.

Specification of Letters Patent. Patented Jan. 11, 1921.

Application filed November 29, 1919. Serial No. 341,429.

To all whom it may concern:

Be it known that I, JARRET C. HOLCOM, a citizen of the United States, residing at Sulphur Springs, in the county of Hopkins 5 and State of Texas, have invented certain new and useful Improvements in Leaf-Turners, of which the following is a specification.

This application is a substitute for an application filed by me September 22, 1915, Serial No. 51,916.

This invention relates to leaf turners and the primary object of the invention is to provide an apparatus which will effectually 15 turn over the leaves or pages of a musical composition without requiring the player to remove his hands from the instrument upon which he is performing.

Other objects of the invention are to provide an apparatus for the stated purpose which will be noiseless and efficient in operation and which will respond instantly to the actuating impulse; to provide novel means whereby the leaves may be mechanically 25 turned in either direction and in proper succession; to provide means whereby the leaves may be quickly and conveniently engaged by the proper leaf-turning arm and may be as easily released after the 30 performance is completed; and to provide an apparatus which may be produced at a low cost and which will not be apt to get out of order.

All these stated objects and other objects 35 which will incidentally appear as the description of the invention proceeds are attained in an apparatus of the character illustrated in the accompanying drawings, and the invention resides in certain novel features which will be particularly pointed out 40 in the claims following the detail description.

In the accompanying drawings:

Figure 1 is a perspective view of a piano 45 having my improved leaf-turning apparatus applied thereto;

Fig. 2 is a view, showing the leaf turner in plan;

Fig. 3 is a rear elevation on a larger scale 50 of the operating mechanism;

Fig. 4 is a detailed perspective view of the means for acting directly upon the leaf-carrying arms;

Fig. 5 is a horizontal section taken on the 55 line 5-5 of Fig. 3;

Fig. 6 is a detailed perspective view of the

mechanism for supporting the book or music while the individual leaves are being engaged by the leaf-turning arms;

Fig. 7 is a detailed perspective view of 60 one of the leaf-turning arms;

Fig. 8 is a vertical section of one of said arms, showing the manner of manipulating the same to engage a sheet.

While I have illustrated the apparatus 65 as applied to a piano, in the accompanying drawings, it is to be understood that such illustration is not a restriction of the scope of the usefulness of the device as it may be fitted to the music-holding stands employed 70 by performers on other instruments and employed by such performers to the same advantage as by piano players.

In applying the apparatus to a piano, I 75 secure to the back or inner side of the piano desk, indicated at 1, a housing 2 in which the mechanism acting directly upon the sheets of music is contained. I also mount in the piano case, near the usual pedals, shown at 3, a pair of pedals 4 which are 80 intended to be actuated by the performer to operate the leaf-turning arms. A housing, shown in dotted lines in Fig. 1 is secured to the inner side of the piano casing and this housing contains a pair of bellows from 85 which flexible conductors or pipes 7 extend to the top of the housing 2, being there fitted over couplings or nipples 8 which extend into the said housing. The pedals 4 project 90 forwardly through openings in the piano case below the panel 10, wear plates 11 being provided around said openings to impart a neat finish thereto.

The nipples 8, to which the upper ends 95 of the respective tubes 7 are fitted, extend through the top wall of the housing 2 and to the inner or lower ends of said nipples I fit flexible tubes 24 which are disposed within the housing and are fitted, respectively, to pneumatic motors or bellows 25. These 100 motors 25 are provided with outwardly opening valves, indicated at 26, so that when a pedal 4 is depressed, the bellows and motor connected thereto will be operated to exhaust the air from the motor and thereby apply a 105 turning force to the leaf-turning arm. A lever arm 27 is secured to and projects upwardly from each motor and the motor is held normally expanded by a spring 28 which is disposed in any convenient manner 110 within the housing 2 and has its upper end connected by a link 29 with the re-

spectively adjacent lever arm 27, the resiliency of the spring tending to force it away from the motor and thereby exerting a pull through the link 29 upon the lever arm 27. The lever arms 27 are connected, respectively, by links or connecting rods 30 with crank arms which form parts of the actuating mechanism for the leaf-engaging arms. As shown most clearly in Fig. 4, the links or connecting rods 30 have turnbuckles or adjusting devices 31 interposed in their length so that the throw of the crank arms may be accurately adjusted, as will be readily understood. The connecting rod 30, which appears at the left of the drawings in the present instance, is connected to a crank arm 32 which extends from a rock shaft or sleeve of any convenient construction, indicated at 33 as a coil wrapped around a pintle or pivot rod 34 which is secured in lugs 35 projecting from a plate or bracket 36 which is secured to the front wall of the housing 2 which, in the present instance, is the piano desk, and is provided near its upper end with an opening 37 through which the operating cams project. From the upper portion of the sleeve or coil 33 extends a second crank 38 from which rises a post 39 which has its upper end secured rigidly to a crank 40 loosely mounted upon the upper portion of the pintle rod 34. This crank 40 is extended radially beyond the post 39 and then merges into a circular actuating member 41 which has its extremity 42 free whereby it may readily pass between adjacent leaf-engaging or carrying arms and on its under side is provided with a shoulder 43 which is adapted to engage the respective leaf-carrying arms and thereby swing the same from one to the other side of the device. The inner end of the connecting rod 30 which appears at the right of the present illustration, is connected to an offset 44 of a crank 45 which has its inner end loosely fitted upon the pintle rod 34 immediately above the sleeve or rock shaft 33 and is, consequently, supported by said sleeve or rock shaft. This crank 45, like the crank 38, has a post 46 rising therefrom and upon the said post 46, near the lower end thereof, I mount a roller 47 which is adapted to ride on the plate 36 and by contact therewith limit the throw of the rock shaft. The upper extremity of the post 46 is secured to a crank 48 loosely fitted upon the pintle rod 34 immediately below the crank 40 and this crank 48 merges at its outer end into a ring or annular actuating member 49 which is provided with a shoulder 50 on its upper side and has its extremity free so that it may readily pass between adjacent leaf-carrying arms. A lifting finger 51 is provided on the post 46 and projects laterally therefrom in position to engage a series of steps or abutments 52 which

are provided in the path of the said lifting finger. These abutments or guides are carried by a plate 53 which is mounted upon standards 54 carried in brackets 55 upon the front wall of the housing 2 and arranged adjacent the bracket or plate 36, as clearly shown. The plate 53 is loosely mounted upon the standards 54 so that it may yield, when necessary, to the lifting finger 51 and thereby prevent breakage of the parts. As shown in Fig. 4, the finger is inclined toward its free end so as to present inclined surfaces to the guides or abutments.

On the front side of the plate or bracket 36 are lugs 56 in which is secured a vertical post or pintle 57 and the several leaf-carrying arms 58 are hung upon the said post through the intervention of cantalivers 59 which are rotatably fitted upon the post. Two cantalivers are provided for each leaf-carrying arm, the upper cantaliver having its outer lower end secured to the outwardly extending portion of the lower cantaliver and the inner portions of said levers being so bent and arranged that they will not interfere with the operation of the several leaf-carrying arms successively. Each lever is provided at its inner end with a ring or eye which fits loosely around the post 57 and the upper horizontal portion of the lower cantalivers are adapted to be engaged by the shoulders 43 and 50 in the operation of the apparatus. As shown clearly in Fig. 4, the eyes of the several cantalivers are so disposed that each eye rests on and is supported by the eye below it and the lowermost eye rests on and is supported by the lower lug 56. The cantalivers may swing about the post 57 as a pivot but they do not move vertically thereon. The leaf-carrying arms 58 are rotatably mounted in hangers 60 which depend from the lower outer portion of the lower cantalivers 59 and each of said arms 58 is provided at its outer free end with a handle or crank 61 whereby it may be manipulated. Secured rigidly to the said arm 58 are jaws 62 which are adapted to engage the sheet of music and each of these jaws 62 is provided with an angular extension or lug 63 which is adapted to bear upon the resilient jaw 64 when the crank 61 is manipulated to turn the parts to the position shown in dotted lines in Fig. 8. The lug or extension 63, bearing against the jaw 64 which is preferably a leaf spring secured rigidly at its upper end to the adjacent hanger 60, will force the said jaw away from the rock shaft or leaf-carrying arm 58 so that the upper edge of a sheet of music may be easily inserted between the jaws. When the sheet is in position, the crank 61 is returned to its depending position and the spring jaw 64 will at once engage the sheet and press it against the jaw 62 so that the sheet will be firmly held. It will be readily understood that the pressure

of the spring upon the lug tends to hold the jaws in either position in which they may be set.

With all devices heretofore produced, so far as I am aware, great difficulty has been experienced in holding the several sheets of music in position to be respectively engaged by the leaf-carrying arms and my present invention provides means whereby the several sheets will be firmly held in position upon the music stand until each sheet has been properly engaged by a leaf-carrying arm. This mechanism comprises presser fingers 65 which are adapted to project through the desk of a piano or through the front of a music stand and when in one position, project over the edge of the book or the several sheets of music and when turned to another position lie flush with or below the surface of the desk and, consequently, offer no obstruction to the turning of the leaves. A knob or other handle 66 is also provided in the piano desk or the music stand so that by rotating this knob in one or the other direction, the presser fingers 65 will be either projected and turned to engage over the music or will be turned from over the music and then withdrawn to the music stand. Preferably, the presser fingers will be arranged to seat in recesses 67 formed in plates 68 secured upon the music stand and the knob 66 will also be arranged within a depression or cavity in a suitable plate 69 provided upon the music stand. The plates 68 form the front members of brackets or guides 70 which extend into the housing 2 and support the slideable rock shafts 71 which have the presser fingers 65 at their front extremities. Upon the inner or rear ends of these rock shafts 71 are cranks 72 which are pivoted to lugs or ears 73 at the opposite ends of a vertically disposed bar 74. Between its ends this bar is hung upon a spring rod or shaft 75 and is held normally toward the end of said shaft by a spring 76 which is coiled around the said spring shaft or rod between a bracket or guide 77 and the vertically disposed bar. This bracket or guide 77 is secured to the front wall of the housing 2 and the outer end of the said spring rod or shaft 75 is held in a bracket 78 also secured upon the front wall of said housing, as shown the said end of the rod being formed into a spring coil 79 having its extremity in the form of a rod 80 secured in the said bracket 78. To the inner end of the spring shaft 75, is pivotally attached a link 81 which is also pivotally attached to a crank 82 on the inner end of a rock shaft 83 which is mounted in a suitable bracket 84 upon the housing 2 and carries a pinion 85 meshing with a pinion 86 on the inner end of a shaft 87 which projects through the housing and carries the knob 66 at its front end. A spring 88 is coiled around the spring shaft

75 and has its ends carried above and below said shaft, as shown at 89, the extremities of these vertically disposed arms 89 being bent horizontally, as shown at 90, to project between the vertically disposed bar 74 and 70 the front wall of the housing and bear upon the said bar with a tendency to press the same rearwardly and hold it away from the front wall of the housing. In each of the brackets 70 and extending parallel with the 75 rock shaft 71 therein, is a guide and stop rod 91 and upon the said adjacent rock shaft I provide stop fingers 92 which project radially from the said rock shaft at an angle of about 45 degrees to each other and are 80 adapted to engage the said guide so as to limit the rotary movement of the rock shaft. When a book or sheets of music are to be secured to the music stand, the knob 66 is rotated and will obviously impart a rotary 85 movement to the shaft 83 through the gearing illustrated and described. The rotation of the shaft 83 will be such that the crank 82 will exert a pull through the link 81 upon the bar 74 against the tension of the spring 90 arms 90. The shafts 71 will, consequently, be caused to slide forwardly through the brackets or guides 70 and the presser fingers 65 will be thereby moved to a position in front of and spaced from the music stand 95 or the front of the housing 2. As the crank 82 swings downwardly and rearwardly past a dead center, it will exert a downward pull upon the link 81 which will in turn impart a downward movement to the end of the 100 spring shaft or carrier 75 and also to the vertically disposed bar 74 connecting the cranks 72 at the inner ends of the rock shafts 71. The downward movement of the bar 74 will, of course, be imparted directly 105 to the cranks 72 which will thereby rotate the shafts 71 so that the presser fingers 65 will be turned to a position over the edges of the several music sheets. As the downward movement of the crank 82 continues, 110 the end of the same will be caused to swing toward the rear of the apparatus and the springs 90 and 79 will then exert their influence upon the bar 74 so as to slide the rock shafts 71 rearwardly and, consequently, draw the presser fingers 65 against the music sheets, thereby clamping the same to the music stand. This position is shown in Fig. 6. The several sheets may then be engaged between the jaws 62 and 64 in the manner previously described and when all of the sheets have been so secured, with the first page of the composition engaged by the jaws hung upon the highest cantaliver, the knob 66 is rotated in a direction opposite 115 to that previously given it. The parts connected with the said knob will, of course, be moved in the reverse directions to that previously taken by them so that the presser fingers will be lifted from the music and 120 125 130

then turned to a vertical position so as to clear the music sheets and then withdraw into their seats or recesses in the music stand.

5 With the parts arranged as in Fig. 1, the performer depresses the right pedal 4 at the conclusion of each page of the composition and thereby successively swings the leaf-carrying arms from the right side of the 10 piano desk to the left side thereof. After the performance is finished, the left pedal will be depressed so as to carry the leaves or sheets successively back to the initial position. The presser fingers 65 may then be re- 15 engaged over the music while the leaf-carrying arms are being disengaged therefrom, said presser fingers being subsequently released from the music so as to permit its removal from the music stand. When a pedal 20 4 is depressed, the bellows connected therewith will be expanded so as to create a suction through the pneumatic motor which is in communication therewith and, consequently, the movable side of the motor will 25 be swung toward the fixed side thereof or the end of the housing 2 and the lever arm 27 will be oscillated so as to exert a pull through the link 30 upon the crank connected therewith. The right pedal 4 is connected 30 with the motor shown at the left in Fig. 3, while the left pedal is connected with the motor shown at the right in said figure. When the motor shown at the left of Fig. 3 is operated, the crank 32 will be swung toward the left and, consequently, the cranks 38 and 40 with the post 39 which, together, 35 constitute a rock shaft, will be swung pivotally around the pintle 34. When this rock shaft is thus actuated, the upper ring 41 will be caused to move in a horizontal plane about the pintle 34 and the shoulder 43 thereof will be brought against the upper cantaliver 59 so as to swing the same out from the music stand or the piano desk and 40 around to the performer's left. It will be understood that in the initial position of the parts, this actuating annular member 41 rests upon the uppermost cantaliver and inasmuch as the crank 45 rests upon the 45 upper end of the sleeve 33, said crank and the actuating ring 49 connected therewith will be held in its uppermost position. The said ring 49, however, will remain at rest while the crank 32 is operating, except that 50 it will move vertically as the said sleeve 33 moves vertically. It will also be understood that the member 41 is inactive when the member 49 is operating but owing to the arrangement of the cranks 38, 40, 45 and 48 55 vertical movement of either actuating member will cause a similar movement of the other member. It will be also understood that the member 41 is always in a horizontal plane immediately above the horizontal plane of a cantaliver and the member 49 is

in a horizontal plane immediately below the horizontal plane of that same cantaliver.

When the pedal is released, the motor will, of course, expand under the influence of the spring 28 and the force of air rushing into the motor, and the crank 32 will, consequently, be returned to its initial position, thereby withdrawing the ring 41 from the leaf-carrying arm. As soon as the free end 42 of the said ring clears the cantaliver 59 which has just swung to the left, the said ring, the ring 49 and the parts connected therewith will drop by gravity so that the portion of the ring 41 in advance of the shoulder 43 will then rest upon the next lower cantaliver. When the pedal is again operated, the second cantaliver, with the leaf-carrying arm connected therewith, will be swung to the left in the manner just described. It will thus be seen that the mechanism has a step by step dropping or descending movement so that it will automatically be in position to engage the cantalivers successively. When it is desired to return the sheets of music to the right side of the piano desk, or the music stand, the left pedal 4 is operated and will cause movement of the motor 25, shown at the right of Fig. 3, as will be understood. When the said motor is actuated under the influence of the pedal, a pull will be exerted upon the crank 45 through the offset 44 so that the rock shaft consisting of the said crank, the post 46 and the upper crank 48, will be swung rearwardly and to the right within the housing 2. The ring 49 is now resting upon the lower wall of the opening 37, having dropped thereon when the ring 41 released the lowest cantaliver. The movement of the crank 48 will, of course, be imparted directly to the ring 49 and the parts associated therewith, the lifting finger 51 riding upon the lowest abutment or guide 52 and being thereby raised so that all the parts will be lifted and the shoulder 51 will be brought into proper position to positively impinge against the lowest cantaliver. It is to be understood that the actuating members 41 and 49 do not make a complete revolution and carry the cantalivers from side to side, but they move through relatively small arcs, although by reason of the sensitiveness of the pneumatic motors, they move rapidly. The cantaliver engaged by an actuating member moves, of course, at the same speed as the member engaging it and the impulse carries it to the opposite side of the desk or stand. During the entire working movement of the ring 49, the lifting finger rests upon the abutment or guide and supports the working parts. When the return movement begins, the impetus of the cantaliver will have carried it under the ring 41 and, consequently, dropping of the parts cannot occur. As the parts return to initial posi- 1

tion, the lifting finger rides under the guide immediately above the guide over which it has just passed, the plate 53 rising to permit the finger to pass but dropping to the 5 lower bracket 55 as soon as it clears the finger so that upon the next working movement, the described lifting action will be repeated.

It is thought the advantages of my 10 proved leaf turner will be readily understood from the foregoing description, taken in connection with the accompanying drawings without further detailed reference to the same and it is to be understood that 15 changes may be made in the minor details of construction or arrangement of parts without involving any departure from the spirit or scope of the invention as the same is defined in the following claims.

20 Having thus described the invention, what is claimed as new is:

1. In a leaf-turning apparatus, the combination of a support mounted to swing in a horizontal plane, hangers fixed to and depending from said support, a leaf carrying arm mounted for rocking movement in the said hangers below the support, leaf-engaging jaws fixed to said arm to rock therewith, and resilient jaws secured to said hangers 30 and depending therefrom past the arm to bear against and coöperate with the first-mentioned jaws to secure a leaf.

2. In a leaf-turning apparatus, a support arranged to swing in a horizontal plane, a leaf-carrying arm mounted for rocking movement on said support, a jaw fixed to said arm, a resilient jaw secured on the support and extending over the first-mentioned jaw to coöperate therewith, and a lug on the 40 first-mentioned jaw bearing upon the resilient jaw whereby to hold the jaws together upon a leaf to be carried, or separated to permit the insertion or withdrawal of a leaf.

3. The combination of a plurality of leaf-carrying arms, a vertically disposed pintle rod, a pair of actuating members, one disposed above and the other below one of the leaf-carrying arms, the upper actuating member being adapted to engage the upper 50 sides of the arms successively and the lower actuating member being adapted to engage the lower sides of the arms successively, rock shafts loosely mounted upon the pintle and secured, respectively to the said actuating members, means connected with said rock shaft to swing the same independently, and means for effecting vertical movement of the rock shafts to bring each actuating member into engagement with the successive 55 leaf-carrying arms.

4. The combination with a plurality of leaf-carrying arms, of upper and lower actuating members arranged to engage said arms, rock shafts connected with the respective actuating members and mounted for in-

dependent rotation, the rock shaft connected with the uppermost actuating member being provided with a sleeve supporting the lower end of the rock shaft connected with the lower actuating member, and means for 70 actuating said rock shafts whereby the actuating member connected respectively therewith will successively engage the leaf-carrying arms.

5. The combination of a plurality of leaf-carrying arms, a vertical series of spaced guides disposed in rear of said arms, upper and lower actuating members adapted to engage the leaf-carrying arms, rock shafts connected respectively with the said members, 75 means acting on said rock shafts to independently rotate the same, the rock shaft connected with the upper actuating member supporting the rock shaft connected with the lower actuating member, and a lifting 80 finger projecting laterally from the last-mentioned rock shaft and adapted to ride upon the said guides successively, the guides and the finger being relatively inclined to effect vertical movement of the rock shaft and 85 raise the actuating members to act upon successively higher leaf-carrying arms.

6. The combination of a pintle, a plurality of leaf-carrying arms supported for movement about said pintle in horizontal 90 planes, a second pintle spaced from the first pintle, a rock shaft consisting of upper and lower cranks mounted to slide upon and rotate about the second pintle and a post connecting said cranks, a second similar rock 95 shaft having its cranks disposed between the cranks of the first-mentioned rock shaft, means connected with the lower ends of the said rock shafts for rotating the same independently, and two members fixed to the upper 100 ends of the respective rock shafts and adapted to move in horizontal planes one of said members carrying means to engage over the leaf-carrying arms successively to move the same in one direction and the other of 105 said members carrying means to engage under the leaf-carrying arms successively to move them in the opposite direction.

7. The combination of a plurality of leaf-carrying arms, a vertical series of spaced 110 vertically movable guides disposed in rear of said arms, upper and lower actuating members adapted to engage the leaf-carrying arms, rock shafts connected respectively with the said members, means acting on said 115 rock shafts to independently rotate the same, the rock shaft connected with the upper actuating member supporting the rock shaft connected with the lower actuating member, and a lifting finger projecting laterally from the last-mentioned rock shaft and adapted to ride upon the said guides successively, the guides and lifting finger being relatively inclined whereby upon movement of the finger 120 in one direction the guides will yield and 125

- upon movement in the opposite direction the finger will ride over the guides and will be thereby moved vertically to raise the rock shafts and the actuating members.
- 5 8. The combination of a plurality of leaf-carrying arms mounted for movement about a common center and having their pivotal portions disposed in different horizontal planes, actuating members arranged one 10 above and one below one of the leaf-carrying arms, means for independently swinging said actuating members across the vertical plane of the leaf-carrying arms, the actuating members being movable vertically 15 whereby each actuating member when in operation will engage and actuate the leaf-carrying arms successively, and means cooperating with the lower actuating member to raise the member step by step.
- 20 9. The combination of a plurality of leaf-

carrying arms mounted for movement about a common center and having their pivotal portions in different horizontal planes, an actuating member arranged adjacent the pivotal portions of the leaf-carrying arms, 25 means for operating said actuating member, a plurality of vertically movable guides arranged adjacent said operating means, and a finger projecting from said means toward said guides, the finger and the guides being 30 relatively inclined whereby on movement of the finger in one direction the finger will ride under a guide and the guides will yield and on movement in the opposite direction the guides will remain stationary and the 35 finger will rise over a guide to cause the actuating member to engage and actuate the leaf-carrying arms successively.

In testimony whereof I affix my signature.
JARRET C. HOLCOM. [L.S.]
